CORE-BREAKING DRILL BIT FOR DOUBLE-
FLUTE AUGERS

Orville Phipps, Adams County, Colo.

Application June 9, 1948, Serial No. 31,876

1 Claim. (Cl. 255—69)

1

This invention is a development from and an improvement over the subject matter of my pending application for United States patent, filed October 29, 1946, Serial No. 706,365, now patent No. 2,578,593, incorporating certain of the teachings of my copending application for United States patent, filed January 6, 1948, Serial No. 681, series of 1948, now abandoned, and has as an object to provide an improved auger-type drill bit susceptible of operative association with and actuation by an auger-type shank or stem of double, spiral flute type.

A further object of the invention is to provide an improved auger-type drill bit adapted for efficient, bore-scavenging cooperation with the helical web terminations of an auger-type drill stem provided with double, spiral flutes.

A further object of the invention is to provide improved core-breaking means in an auger-type drill bit.

A further object of the invention is to provide improved means for operatively and interchangeably associating an auger-type drill bit with the free end of an auger-type actuating stem.

A further object of the invention is to provide an improved auger-type drill bit adapted for the penetration of natural earth beds and strata that is relatively simple and inexpensive of manufacture, susceptible of convenient and repetitious rehabilitation in the field, facile of removal and replacement relative to its actuating means, positive and efficient in use, and susceptible of practical development in a wide range of sizes adapted to particular and specific uses.

With the foregoing and other objects in view, my invention consists in the construction, arrangement, and combination of elements hereinafter set forth, pointed out in my claim and illustrated by the accompanying drawing, in which—

Figure 1 is a side elevation, partly in section to show otherwise concealed construction and relationships, of a preferred embodiment of the invention as mounted on and for practical association with the end of an auger-type actuating stem. Figure 2 is a view similar to Figure 1 typifying an alternative mounting for the bit element relative to its actuating stem. Figure 3 is a side elevation of the bit shown in Figure 1 as dismounted from its actuating stem and at right angles to the Figure 1 showing. Figure 4 is an outer or working end view of the bit shown in Figure 3. Figure 5 is an inner or attachment end view of the bit according to Figure 3.

2

In certain types of mining and earth-boring operations, particularly those involving the development of bores at substantial angles to the vertical, it is conventional and wide-spread practice to employ a straight, spirally-fluted stem powered in rotative driving relation with a cutter or bit interchangeably mounted on the free end of the stem, and to rotate said stem for bore-scavenging removal of drillings through the agency of the stem spiral flutes while simultaneously feeding the stem and bit axially against the work for bore extension consequent upon bit rotation and axial advance. Typical bits applicable to use in the manner described are characterized by radially-offset, spaced fingers projecting in substantial parallelism with the associated stem axis, wear-resistant material arming the free or working tips of said fingers, and an axial mounting shank removably and replaceably engageable with the end of an auger stem, and an efficient, available type of auger stem includes a straight, cylindrical, torque and thrust transmitting core embraced by and constituting the center for double, integrally or fixedly associated, diametrically-opposed, symmetrically and spirally arranged webs or flutes projecting radially therefrom. In the use of such an organization, the bit finger tips cut out an annular zone from the base or foot of the bore, leaving a central core that must be broken away as an incident of bit rotation to facilitate axial advance of the bit, and the double spiral flutes of the auger stem adequately stiffen said stem against deviation and whipping while effectively withdrawing from the bore such cuttings as are fed thereto from and past the bit, hence the instant improvement is directed to the provision of effective core-breaking means and stem-serving, drillings-translating agencies in drill bits of auger type designed for operative association with double-flute auger stems.

In the drawing, a double-flute, bit-actuating, auger stem of the type wherewith the improvements of the instant invention are particularly adapted to be employed is fragmentarily illustrated through a showing of its free end portion wherein the numeral 10 designates the straight, rigid, cylindrical core or center of the stem, which may be either solid or tubular, and the numeral 11 designates the diametrically-opposite, symmetrically-arranged, radially-projecting, spiral webs or flutes fixedly entwining the core 10 in a characteristic manner. The flutes 11 extend to and terminate in the plane of the stem core end wherein they are presented as

relatively narrow radial fingers aligned diametrically of the core, and the end of said core is axially recessed and worked to the form of a coaxial, relatively deep socket adapted to receive and secure the mounting shank of an associated drill bit.

The typical auger-type drill bit interchangeably mountable on and for actuation by the illustrated form of auger stem comprises a normally and preferably integral unit of tractable metal 10 including a laterally-expanded base portion 12 supporting and positioning two or more like cutters or fingers 13 radially offset symmetrically upon and projecting in spaced, generally-parallel relation longitudinally from one side thereof and a mounting shank 14 projecting oppositely to and in parallel relation with said fingers 13 from the center of the other base side. Radially-outward surfaces of the fingers 13 are worked to cylindrical form in a diameter of orbit 20 slightly exceeding that of the stem flutes 11, whereby to develop a bore wherein the stem may rotate and reciprocate without binding, faces of said fingers leading in the direction of bit rotation lie in planes radially of and including the bit axis of rotation, and outer, working end portions of said finger leading faces are armed with blocks or wafers 15 of hard, wear-resistant, alloy material notch-seated and fixed therein with their margins backed by and ground into conformity with the adjacent finger material, said blocks or wafers 15, in any end contour desired, constituting the actual work-performing elements effective to develop the annular cut characteristic of the tool. As shown in Figures 1, 3 and 5, the mounting shank 16 may be worked to angular cross section for telescopic engagement within a corresponding angularly-sectioned socket opening through the end of the stem core 10, in which case registerable holes are provided radially through the socket walls and the shank for the reception of a drive-fit locking pin 16 effective when in place to hold the bit unit to and against separation axially from the stem, the angular interengagement of the shank with its socket transmitting power rotation of the 45 stem to the bit unit without imposing shear stresses on the pin 16. Alternatively, as represented in Figure 2, the shank 14 may be initially cylindrical and worked to the sinusously-profiled, non-binding screw thread form disclosed in my copending application for patent, Serial No. 681, series of 1948, and the socket of the stem correspondingly furnished with a mating screw thread, in which event the interengagement of the shank and socket threads is adequate for the transmission of rotational forces as well as to hold the bit unit against unintended separation from its stem, it being obvious that the shank and socket threads are so pitched as to tighten the joint comprised therefrom during work-performing operation of the assembly.

Giving effect to the principles of the instant invention, the tractable metal of the bit base 12 is worked on the base side from which the fingers 13 project to provide an arcuately-margined ridge 17 bridging diametrically of said base between and in alignment with the rotationally-leading faces of said fingers, and said ridge is centrally intersected by a slot perpendicular to the ridge margin line and the bit axis of rotation opening between and toward the free ends of the fingers 13 wherein a rectangular block 18 of hard, wear-resistant, alloy material formed with a pyramidal tip 19 is seated and fixed, as by means of welding, brazing, or the like, with its tip 19

centered on the axis of bit unit rotation and projected away from the base 12 in the same direction as the fingers 13. The tip 19 of the block 18, spaced inwardly from the working ends 5 of the fingers 13, functions to penetrate and break away the core characteristically resulting from operation of the tool, the angular corners of said tip effectively disrupting the core end engaged thereby as the bit rotates and axially advances, and the form, location, and position of said tip facilitating the sharpening and reconditioning thereof through simple grinding operations performable in the field.

To facilitate and expedite clearance of cuttings from the foot or base of the bore under development by the tool and to effectively feed said cuttings to the channels between the double flutes of the auger stem for full utilization of the scavenging advantage of the latter, the bit base 12 is formed and worked to provide spiral wings trailing the fingers 13 for operative registration with the terminal fingers of the stem flutes 11, thereby, in effect, extending said flutes through the bit base. The spiral wings above noted result from a shaping of the bit base material in a manner to continue the rotationally-leading faces of the fingers 13 as planes radial of the bit axis through the base 12 save at the inner end and side junctions of said faces with the central zone of the base where said faces merge through concave areas into and with the adjacent base central portion to deeply indent and interrupt the orbitally circular outline of the base. Spacedly-opposed, inner margins of the fingers 13 define planes substantially perpendicular to the associated finger leading face and extending in width to intersection with the generally-cylindrical outer finger surface, thereby defining a rearwardly-tapered finger body thickened in the arc of its rotation, and said finger inner margin planes traverse the length of the associated finger to the intersection of the ridge 17 therewith and thence merge as spirally-concaved, rearwardly and outwardly directed surfaces with and through the base 12 thickness to intersection with the opposite side of said base in substantially straight margins or edges 20 approximately perpendicular to and merging with the concave base junctions of the adjacent finger leading face, the slope of said spirally-concaved faces leading to the edges 19 simulating the pitch and contour of the flute 11 radial surfaces. Complementing and completing the operative effect of the spirally-concaved bit base surfaces, the radially-extending side of the base 12 remote from and beneath the fingers 13 is outwardly and axially spiraled to slope toward the shank end of the unit from each finger leading face intersection with the base to emergence in and with the associated trailing edge 29. As will be apparent, the edges 20 are designed to operatively register with the terminal fingers of the stem flutes 11 when the bit is shank-mounted on the end of said stem, thereby to establish continuous spiral channels from the throat of the bit to and along the stem, and such registration is a natural and invariable consequence of proper correlation, at the time of element manufacture, between the rotationally-interlocking elements, whether screw threads or angularly-related surfaces, of the interengageable shank and socket members.

The improved bit unit formed, constructed, and arranged as shown and described functions in mounted association with a power-rotated, double-flute drill stem to develop and extend a bore with enhanced facility and efficiency. The

armed tips of the fingers 13 cut out the customary annular zone at the foot or base of the bore and the spirally-concaved areas trailing the finger bases feed the cuttings directly and immediately to the spiral scavenging channels of the stem to fully and effectively clear the bit working area and obviate any hampering congestion which might retard cutting action, while the tip 19 of the block 18 rapidly and efficiently disintegrates the end of the core produced centrally of said annular zone, breaking the fragments of said core into the scavenging channels for prompt evacuation from the bore.

Since many changes, variations, and modifications in the specific form, construction, and arrangement of the elements shown and described may be had without departing from the spirit of my invention, I wish to be understood as being limited solely by the scope of the appended claim, rather than by any details of the illustrative showing and foregoing description.

I claim as my invention:

In an auger-type drill bit having a body of tractable metal formed with angularly-spaced, radially-offset, like fingers outstanding in spaced parallelism of their inner side margins with its axis for generation of an annular trough cut as an incident of body rotation, means rotatable with said body to disrupt the core of material centrally of said trough cut, said means comprising a pyramidal block of alloy material formed

with a rectangular base portion, an axially-opening slot diametrically of said body between said fingers for the fitted reception of said block base portion, whereby to mount said pyramidal block as a coaxial projection from said body spacedly adjacent and between the body-fixed ends of said fingers, and a permanent bond uniting engaged surfaces of said slot and block base portion.
